CLAIM

We claim the ornamental design for a light fixture, as shown and described.

DESCRIPTION

FIG. 1 is a bottom, rear, left perspective view of the claimed design;

FIG. 2 is a bottom plan view thereof;

FIG. 3 is a top plan view thereof;

FIG. 4 is a left elevation view thereof;

FIG. 5 is a right elevation view thereof;

FIG. 6 is a front elevation view thereof; and,

FIG. 7 is a rear elevation view thereof.

The broken lines in the drawings illustrate portions of the light fixture which forms no part of the claimed design.

1 Claim, 5 Drawing Sheets
